[75] Inventor: **Craig A. Stapleton**, Port Huron, Mich.

Primary Examiner—James M. Gandy

Attorney, Agent, or Firm—Edgar A. Zarins; Malcolm L. Sutherland

[73] Assignee: **Huron/St. Clair Incorporated**, Port Huron, Mich.

[57] CLAIM

The ornamental design for a luggage carrier support stanchion, as shown and described.

DESCRIPTION

FIG. 1 is a perspective view of a luggage carrier support stanchion showing my new design;

FIG. 2 is a side elevation view thereof;

FIG. 3 is a top plan view thereof;

FIG. 4 is a side elevation view thereof opposite to that shown in FIG. 2;

FIG. 5 is a bottom plan view thereof;

FIG. 6 is an end elevation view thereof; and

FIG. 7 is an opposite end elevation view thereof.

[**] Term: **14 Years**
